United States Patent Office

Des. 210,544
Patented Mar. 19, 1968

210,544

SKI SCOOTER

Samuel Fleisher, 2812 Ardmore,
Royal Oak, Mich. 48073

Filed Nov. 21, 1966, Ser. No. 4,758

Term of patent 14 years

(Cl. D34—15)

FIG.1

FIG.2

FIG.3

FIGURE 1 is a front perspective view of the ski scooter showing my new design;

FIGURE 2 is a side elevational view of the ski scooter shown in FIGURE 1, on an enlarged scale; and

FIGURE 3 is a view of the ski scooter from the horizontal plane 3—3 of FIG. 2.

I claim:

The ornamental design for a ski scooter, substantially as shown.
